UNITED STATES PATENT OFFICE.

LEROY L. MARTIN, OF PATERSON, NEW JERSEY.

TOOL HANDLE OR HOLDER.

Application filed February 21, 1922. Serial No. 538,160.

To all whom it may concern:

Be it known that I, LEROY L. MARTIN, a citizen of the United States, residing at Paterson, in the county of Passaic and State of New Jersey, have invented certain new and useful Improvements in Tool Handles or Holders, of which the following is a specification.

This invention relates to handles or holders for tools and it has for its object to provide a handle or holder for safety razor blades that can be manufactured and sold at a trifling cost and that will obtain an effective grip on the blade and afford to the user's hand a comfortable as well as secure grip thereon. The device may be formed according to my invention from a simple rectangular blank of stiff sheet material by simply slitting the same once and then folding and bending the blank.

A further object is to provide, at as little additional expense as possible, a sheath or guard for the working edge of the blade.

In the drawing,

Fig. 1 is a perspective view of the improved handle or holder, showing a razor blade held therein and also a guard on the working edge of the blade;

Fig. 2 is a plan of the blank from which the handle or holder is formed;

Fig. 3 is a plan of the completed handle or holder;

Fig. 4 is a side elevation thereof, partly in section, showing a blade in position;

Figs. 5 and 6 are sectional views on lines 5-5 and 6-6 of Fig. 4, Fig. 5 also showing a certain sheath in section;

Fig. 7 shows the blank from which the said guard may be formed; and

Figs. 8 and 9 are a side elevation and a plan of a modified form.

a designates an oblong blank of sheet metal. From one end along the line of its central longitudinal axis and for a distance representing somewhat more than one-half its length this blank is formed with a slit *b*.

The blank is then folded on the line of its central longitudinal axis, as at *c*, Fig. 3, so as to bring its portions *a'* *a'* which have been left transversely connected into face to face relation to each other but preferably sufficiently spaced so that a blade can be wedged in between them, it being contemplated in the preferred form of the invention

that a certain degree of inherent elasticity in the metal of the blank shall cause the portions or walls *a'* *a'* to hold the blade entered between them. If desired the free end edges of the portions or walls *a'* *a'* may be turned inwardly and abut each other, as in Fig. 6, to close the outer end of the blade pocket *d* that is formed between said portions.

Having thus formed the holder proper *A* of the device, the portions *a²* *a²* of the blank, which originally lie both sides of the slit *b* and now form extensions of the fold-forming portions *a'* *a'*, are sprung apart so as to stand as to the major part of their length converging in the direction of the said holder proper (see Fig. 3), their outer extremities being bent toward and made to abut each other end to end, as indicated at *a³*; preferably their ends at this point are soldered together, as shown at *e*. Thus the portions *a²* *a²* come to form the handle proper *B* of the device.

The blade *f* illustrated is a double-edged sheet metal blade of the so-called Gillette type (my invention is however not limited to this particular type of blade).

It is introduced into the holder proper of the holder or handle in an obvious manner and when in place stands clamped between the portions or walls *a'* *a'* thereof and abutting the bottom or back of the pocket *d* formed by the fold *c*. In many uses of the implement formed by the assembled holder or handle and blade it will be desirable to positively prevent slippage of the blade outward or away from the handle proper, and to this end the abutting end edges of the portions *a'* *a'* may act as a stop *g* for the blade.

When the implement formed by the assembled blade and handle or holder is not in use the exposed edge of the blade may be sheathed in a guard *h* formed by folding on its central longitudinal axis the oblong sheet-metal blank *i* shown in Fig. 7, the opposite walls produced by this folding being adapted to clamp the blade introduced between them and so retain the guard in place. The object underlying the slitting of the blank at *b* and the bending of the portions *a²* *a²* is to give the handle greater transverse dimension or thickness than it would otherwise have and thus afford a more com-

fortable and secure grip to the hand of the user.

In the modified form shown in Figs. 8 and 9 the handle or holder may be formed from a blank exactly like that shown in Fig. 2, which will be folded on line *c* the same as before, thereby producing the blade holder proper *A'*. But to produce the handle proper *B'* the portions separated by the slit *b* are first bent outwardly convergently, as at *x*, then made to extend parallel with the plane of the holder proper *A'*, as at *y*, and then bent inwardly, as at *z*, their free ends meeting and if desired being soldered together. A modified form of sheath *i'* is also shown, being formed from a blank simulating the blank *i* excepting that at one end it has lateral projections *i²* which, on folding the blank in the same manner as blank *i*, are preferably spaced nearly as far as are the portions *y* of the handle or holder. Through these projections and said walls or portions *y*, near their inner ends, a riveted pivot *j* is passed, the spaced-apart projections giving a certain desirable stability to the sheath, especially against sidewise displacement. The sheath may turn on a pivot *j* into housing relation to the working edge of the blade or into completely housed relation to the handle proper *B'*.

Having thus fully described my invention, what I claim as new and desire to secure by Letters Patent is:—

1. A tool holder consisting of a folded piece of stiff sheet material having its fold-forming portions standing face to face and adapted to grip between them the tool to be held and having extensions projecting from said portions lengthwise of the fold and one of said extensions deflected away from the other, said extensions thereby forming a handle proper of greater thickness than the folded part of the piece.

2. A tool holder consisting of a folded piece of stiff sheet material having its fold-forming portions standing face to face and adapted to grip between them the tool to be

held and having extensions projecting from said portions lengthwise of the fold and one of said extensions deflected away from the other, said extensions thereby forming a handle proper of greater thickness than the folded part of the piece and one of them having its free end bent toward and bearing against the other. 55

3. A tool holder consisting of a piece of stiff sheet material having a part thereof folded and adapted to grip between the fold-forming portions thereof a blade having its edge protruding laterally, said portions having extensions projecting therefrom longitudinally of the fold and spaced from each other, in combination with a sheath for the blade consisting of a piece of folded stiff sheet material projecting between and pivoted to one of said extensions on an axis substantially perpendicular thereto, said sheath when turned on said axis in one direction being adapted to be housed substantially entirely between said extensions and when turned in the other direction being adapted to house the blade edge. 60

4. A tool holder consisting of a piece of stiff sheet material having a part thereof folded and adapted to grip between the fold-forming portions thereof a blade having its edge protruding laterally, said portions having extensions projecting therefrom longitudinally of the fold and spaced from each other, in combination with a sheath for the blade consisting of a piece of folded stiff sheet material having projections spaced further than its fold-forming portions and extending between and pivoted to said extensions on an axis substantially perpendicular thereto, said sheath when turned on said axis in one direction being adapted to be housed substantially entirely between said extensions and when turned in the other direction being adapted to house the blade edge. 75

In testimony whereof I affix my signature.

LEROY L. MARTIN.
